US0D1077909S

(12) **United States Design Patent** (10) **Patent No.:** **US D1,077,909 S**
(45) **Date of Patent:** **** Jun. 3, 2025**

(54) **NAME TAG FOR STETHOSCOPE**

(71) **Applicant:** **WUXI KAISHUN MEDICAL DEVICE MANUFACTURING CO., LTD.**, Wuxi (CN)

(72) **Inventor:** **Xijie Shan**, Jiangsu (CN)

(73) **Assignee:** **WUXI KAISHUN MEDICAL DEVICE MANUFACTURING CO., LTD.**, Wuxi (CN)

(**) **Term:** **15 Years**

(21) **Appl. No.:** **35/518,786**

(22) **Filed:** **Jul. 24, 2023**

(80) **Hague Agreement Data**

Int. Filing Date: **Jul. 24, 2023**

Int. Reg. No.: **DM/232326**

Int. Reg. Date: **Jul. 24, 2023**

Int. Reg. Pub. Date: **Oct. 27, 2023**

(57) **CLAIM**

The ornamental design for a name tag for stethoscope, as shown and described.

DESCRIPTION

The patent or application file contains at least one drawing executed in color. Copies of this patent or patent application publication with color drawing(s) will be provided by the Office upon request and payment of the necessary fee.

1.1 is a top plan view of a name tag for stethoscope showing my new design;

1.2 is a bottom view thereof;

1.3 is a left-side view thereof;

1.4 is a right-side view thereof;

1.5 is a back view thereof;

1.6 is a front view thereof;

1.7 is a top back perspective view thereof; and

1.8 is a bottom front perspective view thereof.

**1 Claim, 8 Drawing Sheets
(8 of 8 Drawing Sheet(s) Filed in Color)**
